UNITED STATES PATENT OFFICE.

JOHN SHELLENBERGER, OF ROME, GEORGIA, ASSIGNOR TO SEALED CASE COMPANY, A CORPORATION OF NEW YORK.

BINDING-WIRE-CUTTING MECHANISM FOR WIRE-BOUND-BOX-BLANK MACHINES AND THE LIKE.

1,416,419.

Specification of Letters Patent. Patented May 16, 1922.

Application filed February 20, 1919, Serial No. 278,187. Renewed August 13, 1921. Serial No. 403,298.

To all whom it may concern:

Be it known that I, JOHN SHELLENBERGER, a citizen of the United States of America, and resident of Rome, Floyd County, State of Georgia, have invented certain new and useful Improvements in Binding-Wire-Cutting Mechanism for Wire-Bound-Box-Blank Machines and the like, of which the following is a specification.

10 This invention relates to certain improvements in wire bound box blank machines; and the objects and nature of the invention will be readily understood by those skilled in the art in the light of the following explanation of the accompanying drawings illustrating what I now believe to be the preferred mechanical expression or embodiment of my invention from among other forms, constructions and arrangements 20 within the spirit and scope thereof.

Wire bound box blanks of commerce comprise sheets of thin lumber or veneer traversed by several rows of binding wires stapled to the sheets of a blank and continuous 25 throughout the length thereof. These blanks are produced in flat form of a length to bend along transverse lines usually so that each blank will fold up to form all four side walls of a receptacle or box. The

30 blanks are usually produced by machines wherein the assembled sheets and binding wires are fed forward step by step through stapling mechanism periodically operative to apply the staples while the blanks are at 35 rest between the feeding steps or strokes. The machines complete these blanks in succession, one after the other, usually with a more or less certain or predetermined spacing between the blanks. The binding wires

40 are drawn from reels or spools by the forward or feeding movements of the blanks and hence the binding wires are continuous from each completed stapled blank as it passes forward from the stapling mechanism 45 to the succeeding blank, bridging the space between the completed blank and the succeeding blank. In order to remove and separate the completed blanks it is hence necessary to sever these binding wires joining 50 the completed blank with the blank that follows.

It is an object of my invention to provide wire bound box blank machinery with mech-

anism for automatically severing these wires.

A further object of the invention is to provide improvements in wire cutters applicable to wire bound box machinery for severing the binding wires.

With these and other objects in view my invention consists in certain novel features in construction, combinations and arrangements as more fully and particularly pointed out and specified hereinafter.

Referring to the accompanying drawings:

Fig. 1 is a conventional or diagrammatical showing of a wire bound box blank machine, parts being omitted and other parts indicated by dotted lines, one of the frame uprights being broken away to show the cutting mechanism of my invention.

Fig. 2 is a detail view of a portion of the cutter operating mechanism.

Fig. 3 is a horizontal section through a portion of the machine.

Fig. 4 is a detail rear elevation of the cutting mechanism, the machine bed, rails and feed chains being shown in section, the cutter blades being shown approximately in normal positions, a stapled box blank being 80 shown in end elevation with the binding wires in section.

Fig. 5 is a detail vertical section through the slide and fixed bars and the blocks of the cutting mechanism.

Fig. 6 is a detail top plan of the slide block and certain adjacent parts, some of said parts appearing in horizontal section, the latch or trip being shown in dotted lines, the block and latch being shown in 90 their normal positions.

Fig. 7 is a detail view showing the slide block forced back by the feed chain to the position it assumes while the wire cutting operation is being performed, the vertically 95 reciprocatory rack that actuates the cutters being shown in cross section and in mesh with the toothed sector.

Fig. 8 is a detail view showing the slide block at its limit of forward movement during the next forward step of the chain after the wire cutting operation, the trip or latch being shown by dotted lines in tripped chain-lug-releasing position just before the spring returns said slide to normal position.

Figs. 9, 10, and 11 are detail elevations

showing respectively a cutter in normal position, in position approximately midway the cutting stroke, and in final cutting position just before the cutting mechanism starts 5 on the return stroke.

In the particular example illustrated, I show a wire bound box machine embodying frame uprights 1, stapling mechanism 2, operated by means of a reciprocating cross 10 head 3, to periodically apply staples to the binding wires *a* and sheets of lumber *b*. The cross head is reciprocated vertically by one or more pitmen 4, having crank or eccentric connections 5 with the main drive 15 shaft 6. The binding wires *a* are fed or drawn from spools 7 and pass through the stapling mechanism with the sheets *b* and are secured thereto by the staples *c* applied by said mechanism. The sheets of lumber 20 move longitudinally through the machine in a suitable guideway usually formed or established by elongated parallel horizontal rails 8. The sheets are advanced step by step along said rails and through the stapling 25 mechanism by any suitable means, although in this example I show endless traveling link belts 10 for this purpose. The forwardly moving upper lengths of these belts travel in depressed channels in said rails and the 30 sheets rest on and are carried or conveyed forward by the belts. The conveyer formed by the belts is supported in any suitable manner, as by sprocket wheels, and is driven in any suitable manner, as by pawl and 35 ratchet mechanism operatively connected in any suitable manner with the main drive shaft 6 to advance the conveyer step by step and time the movements thereof with respect to the stapling mechanism so that the conveyer and blanks carried thereby will be at 40 rest while the staples are being applied and so that the conveyer and blanks will make their forward feeding strokes or steps while the stapling mechanism is making its return 45 stroke and possibly starting on its operative stroke.

The conveyer is provided with means to locate, gage or determine the front end or beginning of each box blank, and where the 50 conveyer is provided with several such means, they are spaced apart longitudinally of the conveyer a distance equal to the length of a completed blank plus the desired spacing between the rear end of a completed 55 or stapled blank and the front end of the succeeding blank which may be only partially stapled. This spacing distance is usually about four inches more or less. In the example illustrated, each such stop or gage 60 means can consist of one or more upwardly projecting lugs 15, fixed to and moving with the conveyer.

Where each link belt is formed with such lugs, the lugs constituting each means are 65 alined transversely of the conveyer. In as-

sembling the sheets on the conveyer at the sheet receiving end thereof, the first sheet of each blank is pressed forward against said lug or lugs and the remaining sheets of a complete blank are thereafter successively 70 arranged and assembled on the conveyer, and when the last sheet of a complete blank has been assembled on the conveyer, no more sheets are assembled on the receiving end of the conveyer until the next lug 15 on the 75 conveyer advances to sheet receiving position whereupon the first sheet of the next blank is assembled on the conveyer against the rear edge of said lug, hence the spacing or empty space on the conveyer between the 80 rear end of a blank and the following lug 15 at the front of the preceding blank.

These lugs are of greater length vertically than the thickness of the sheets and hence project above the same. Sometimes the conveyer is provided with shorter spacing lugs 15' to determine the spacings between different sections of a blank, but where employed these lugs 15' are vertically short and do not project above the sheets on the conveyer.

According to my invention, I provide means for cutting the binding wires that join a stapled or completed blank with the following blank and I arrange such wire 95 cutting means at any suitable portion of the machine along the conveyer beyond the outlet or discharging side of the stapling mechanism. In the example illustrated, I locate the cutting mechanism near the stapling mechanism but beyond the same in the direction of blank feed, and provide separate cutters for each binding wire.

For instance, in the drawings, I show three binding wires and hence I provide three 105 cutters spaced according to the binding wire spacing. Each cutter consists of a block 20 above the binding wire having a lower approximately horizontal cutting edge 20' arranged transversely with respect to the wire, 110 and an elongated vertically swingable blade 21 at one end fulcrumed at 21' to one end of the block. This blade tapers to its free end and has a top cutting edge 21^a terminating in a wire holding and cutting shoulder 21^b. 115 The flat face of the blade closely fits the vertical flat face of the block and as the blade swings upwardly its cutting edge cooperates with the bottom edge 20' of the block to shear the wire, as more fully appears hereinafter. 120 Any suitable means can be provided to adjustably support and operate these cutters. In the example illustrated, I show alined fixed vertical posts 22 arranged beyond the opposite edges of the sheet lumber or blank 125 guideway. These posts are formed with alined transverse guides or slideways 23 receiving a longitudinally reciprocatory horizontal bar 24 arranged transversely of said guideway and above the horizontal plane of 130

the top surfaces of the blanks traveling in said guideway. The side of this bar is formed with a longitudinal dovetailed or undercut groove 25. The blocks 20 are arranged along the bar 24 and are clamped to the side face thereof by bolts 26 having tapered heads in the groove 25. By loosening the nuts on these bolts each block can be independently adjusted longitudinally of the bar, the bolt heads sliding in the groove. The blocks can thus be adjusted to various positions along the bar as rendered necessary by the positions and spacing of the binding wires. Also blocks and cutters can be added where the number of binding wires is increased.

Above and parallel with the reciprocating bar 24 is a fixed bar 27 secured to the posts 22 and formed with a longitudinal dovetailed groove 27^a. This bar 27 carries blocks 28, one for each block 20 and arranged above the same. The blocks 28 are normally clamped rigidly to but are individually adjustable longitudinally of bar 27 through the medium of bolts 28^a having heads slideable in the groove 27^a. The blades 21 are swung on their various strokes by links 29 depending at the faces of the blocks and blades and at their upper ends pivoted to the blocks 28 and at their lower ends pivoted to the free end portions of the blades.

As hereinafter appears, suitable means are provided for reciprocating the slide 24 an operative stroke when the portions of the binding wires to be severed arrive at the cutting station, i. e., when the feeding mechanism comes to rest with the space between a stapled blank and the succeeding blank located under the cutting blades. On its operative stroke, the slide 24 moves from its normal position, at its limit of movement in one direction, to its limit of movement in the opposite direction and then returns to normal position. This operative stroke of the slide, opens the cutters and advances the blades to positions below the binding wires, closes the cutters to sever the wires by swinging the blades to their limits of upward movement, and then returns the blades to normal inoperative positions out of the way of the advancing blanks and binding wires. The blades are thus swung and controlled by the reciprocation of the slide through the medium of the links 29 at their upper ends pivoted to the relatively fixed blocks 28 and support 27. When the slide 24 is at rest in normal position, the links 29 are inclined from vertical position and the blades are thereby held elevated with their points beside blocks 20. The blades in normal position are held elevated above the blanks and each blade is withdrawn to one side of the line of the binding wire which it is adjusted to sever on its operative stroke. The blades thus remain inoperative and entirely withdrawn from the

paths of the advancing sheets and binding wires stapled thereto, until the rear end of a completed blank passes under said blades and comes to rest with the space unoccupied by sheets that exist between said blank and the front end of the following blank, located below the blades. This space is bridged by the binding wires that are to be severed to free the said completed blank. While the feed mechanism is thus at rest between feed strokes with this unoccupied space below the blades and while the stapling mechanism is performing an operative stroke, certain devices cause an operative stroke of the slide 24. The forward movement of the slide moves the points of free ends of the blades toward the binding wires to be severed thereby and as the links 29 swing down toward the vertical position said blades are swung down into said unoccupied space so that the free ends of the blades are below the planes of the wires by the time said links assume the vertical position. The shears or cutters are then wide open to receive or straddle the wires and are advancing toward the wires during this movement so that the points of the blades slip under the wires and force the wires into the bite between the blades and edges 20' of the shear blocks 20. The continued movement of the slide 24 carries the links beyond the vertical and the blades are thereupon swung upwardly to sever the wires by the shearing action of the cooperating edges of the blades and shear blocks in which operation the shoulders 21^b serve to hold the wires from slipping past the free ends of the blades. The cutting or shearing action has been completed by the time the slide reaches its limit of movement opposite normal position, and the slide thereupon returns on its back stroke to normal position with the blades withdrawn. This complete stroke of the slide occurs before the feed mechanism starts on its next forward feeding stroke or step.

It will be observed that all of the cutters or shears move in unison in performing their operations and that an exceedingly powerful toggle or lever arrangement is provided for operating the blades. It will also be observed that the positions of the blades can be accurately attained by relative adjustments between the blocks 20, 28 of each shear or cutter, also that the position of each shear or cutter can be accurately adjusted with respect to the wires; also that the number of cutters or shears can be increased or diminished by removal or addition of cutters to the bars because, in this instance, of the provision of the longitudinal dovetailed grooves opening through ends of the bars.

Any suitable means can be provided for actuating the slide 24 to perform an operative stroke and for timing the operation

thereof with respect to the movements of the feed mechanism and the location of the spacing between blanks. In the example illustrated, I utilize the stapling mechanism 5 cross head 3 for causing the operation of the slide 24 and time this operation by the position of the blank gage or stop 15, although I do not now wish to so limit and restrict 10 all features of my invention. In this form of my invention, operative or power transmission connection is established between the said reciprocating cross head and the cutter or shear operating slide, and this operative connection includes or embodies a 15 clutch or make and break device whereby the operative connection is normally out of action or inoperative. The gage 15 is utilized to throw this clutch or make and break device into action or operative position to 20 establish operative connection between the cross head and slide when the space between a completed blank and the following blank is located below the cutters.

In the example illustrated, the slide 24 is 25 reciprocated by a long link or pitman 30, at one end pivoted to the slide and at the other end pivoted to the free end of an upwardly extending crank arm 31 rigid with a rock shaft 32 mounted in a slide block 33, 30 and provided with a toothed sector 34, at its lower end having projecting or long tooth 34'. This sector is adapted to be operatively engaged and swung by rack 35 fixed to and depending from cross head 3, when said sector and rack are brought into operative 35 alinement or positioning. The rack and sector are of such relative formation and dimensions as to operate the slide a complete stroke or reciprocation when the cross head 40 makes a complete stroke, or down and return movement, provided the rack and sector are operatively alined.

The slide block carrying rock shaft 32, is carried by a suitable bracket 36, secured to 45 one of the frame bars and formed with a guideway 37, parallel with the direction of feed of the blanks. The slide block is confined to said block by said guideway to a limited sliding movement parallel with the 50 direction of blank feed. This longitudinal movement of the block is at least sufficient to throw the sector into and out of alinement with the vertical rack 35. The block is normally held in inoperative position with 55 said sector and rack out of alinement, by any suitable means, such as spring 38. This spring holds the block back in inoperative position against a suitable stop. The lower end of the vertical rack is located a distance 60 above the sector when the cross head 3 is in normal elevated position and during the normal operation of the machine (when the block is in inoperative position) the rack moves up and down beside the sector without

engaging the same as the cross head reciprocates. When the slide block is thus in inoperative position, the cutter operating slide is held in normal inoperative position by spring 40 which also holds the rock shaft 32 with its sector 34 elevated and its crank arm 70 31 swung outwardly.

Suitable means are provided to move the slide block forwardly to bring the sector 75 34 into alinement with the rack 35 as the feed mechanism makes its stroke that brings 80 said space immediately following a completed blank, to position below the cutters. For this purpose, in the example illustrated, I show a trip or latch 41, pivoted at 41' to the slide block and arranged to be engaged 85 and moved by the gages or stops 15 to force the slide block forwardly to said operative position and there hold the same while the feed mechanism is at rest with said space 90 below the cutters. This latch 41 is formed 95 with a free rear end constituting an abutment 41^a normally located in the path of the lug 15 (or other operating means indicating or gaged by the space intervening between a stapled blank and the front end of the next blank). In the particular example 100 illustrated, the latch or lever 41 is horizontally arranged and swingable and is located immediately over one of the feed chains 10 and out of contact with the box blanks and 105 with said chain, excepting the particular lug or lugs of said chain that are designed to engage said abutment end 41^a to operate the slide block. The arrangement is such 110 that just before the portions of the binding wires to be cut reach cutting position below the blades 21, the lug 15 (or other gage device) will engage the abutment end 41^a, of the latch 41 and thereby push the block 115 33 forward with the feed chain until the toothed sector 34 is in alinement with rack 35. The feed mechanism (chains 10) will 120 then come to rest and the portions of the binding wires to be cut will be located at cutting position under blades 21. The lug 15 will hold the slide block in this position while the chain is at rest and while the binding wire cutting operation is being performed. The slide block during this binding wire cutting operation will be in approximately the position indicated by Fig. 7.

The binding wire cutting operation is completed before the feed mechanism (chains 10) starts on its next forward or feeding step, and means are provided to automatically release the slide block from the feed mechanism during said next feeding step, so that said slide block can be automatically moved back to normal position (Fig. 6) by its spring 38. Various means can be provided for thus releasing the slide block for return to normal position, although in the specific example illustrated, I show the front free

end 41^b, of the latch or lever extending forwardly beyond the slide block and slideable under a bracket 48 formed with a cam slot 41^c, in which a pin 46 carried by said end 5 of the lever slides. The rear portion of this slot 41^c is straight and parallel with the direction of feed and is formed to normally hold the lever 41 in operative position to engage lug 15, and also to hold said lever 10 in normal position while the block is being moved to bring the toothed sector into alignment with the rack (Fig. 7). The front end portion of said slot is inclined laterally to swing the lever 41 (through the medium 15 of pin 46) laterally to throw its rear end 41^a clear of the lug 15 (Fig. 8) and thus release the slide block when said block is carried forward during a portion of said next feeding step of the feed mechanism.

20 When the lever 41 has thus been tripped to release the block from the lug 15, the spring 38 returns the block to normal position and during this return movement, the inclined portion of said slot swings the lever 25 41 back to the normal position (Fig. 6). The bracket 48 is carried by the frame bar or rail 8 to which bracket 36 is secured. In the example illustrated, these two brackets are bolted to the outer edge or vertical portion 30 of said rail and extend inwardly above the rail to overhang the path traveled by the box blanks, and are independently adjustable longitudinally of said rail. For instance, the clamping bolts for the brackets 35 can have enlarged heads slideable in an undercut longitudinal groove in said edge portion of the rail.

The means for throwing the cutting mechanism into gear with its operating means, 40 can be operated by any suitable means moving with the feed mechanism and timed by the passage of the rear end of a stapled blank past the cutters or by the approach of the front end of the succeeding blank 45 toward the cutters. I do not wish to limit my invention to utilizing the particular lug 15 that is engaged by the blank, as the means to engage the lever 41.

In the conventional showing of a wire 50 bound box blank machine, I conventionally illustrate ratchet mechanism for propelling the feed chains step by step. For instance, I show ratchet wheel 49 driving said chains and actuated from main shaft 6 through 55 the medium of crank connection 50, link or pitman 51, rocking pawl carrier 52 and pawl 53.

In the particular example illustrated, the long pitman 30 and its joints with crank 60 arm 31 and slide 24, provide sufficient flexibility to permit the back and forth movement of the slide block carrying rock shaft 32.

Also in the particular example illustrated,

the toothed sector 34 is provided with the 65 long lower tooth or projection 34' to be engaged by the lower end of the descending rack and thereby swing the sector to bring its teeth into position for meshing with the teeth of the rack and for other reasons, although I do not wish to so limit my invention.

70 It is evident that various changes, modifications and variations might be resorted to without departing from the spirit and scope 75 of my invention and hence I do not wish to limit myself to the exact disclosures hereof.

What I claim is:—

1. In a wire bound box blank machine, a 80 periodically operating stapler having a reciprocating part moving therewith provided with a rack, feed mechanism for advancing sheets of lumber and binding wires through the stapler for the production of wire bound blanks, normally-inactive cutters for severing the binding wires behind each stapled blank, normally inactive means for actuating said cutters to perform a wire severing operation and then returning the same to inactive position, said means including a 85 toothed sector adapted to mesh with and be operated by said rack but normally out of operative position with respect thereto, and automatic means for temporarily establishing operative relation between said sector 90 and rack.

2. Mechanism for cutting wire bound box blank binding wires where such wires bridge the space between the rear end of a stapled 100 box blank and the advancing end of the succeeding blank, comprising a longitudinally-reciprocating slide arranged transversely of and out of the paths traversed by the wires to be severed, said slide provided with means providing cutting edges transversely arranged with respect to said paths, swinging free end cutting blades carried by said slide, means controlling the swing of said blades as the slide longitudinally reciprocates, and operating mechanism for said slide, said 105 blades normally arranged beside said edges and to one side of the paths of said wires and adapted on the reciprocation of said slide and under the control of said means to swing away from said edges and move to positions 110 with the wires between the free ends of the blades and the edges and to then close on the wires between the edges and blades to sever the same.

3. In a wire bound box blank machine, 120 binding wire cutters comprising blades arranged over the path of the blanks and binding wires and normally withdrawn from operative position with respect thereto, means above said blanks and wires to cooperate 125 with said blades in shearing said wires, each blade having a free end, and actuating and controlling means for swinging the blades

downwardly and advancing them laterally to project their free ends under the wires and to then swing the blades upwardly to sever the wires and to finally return the blades to 5 normal withdrawn position.

4. In a wire bound box blank machine, binding wire cutters comprising shear blocks adjustable toward and from each other and held against vertical movement, a support 10 for said blocks, means normally securing said blocks, respectively, to said support against movement independently thereof and whereby said blocks are rendered independently adjustable, normally-horizontally- 15 disposed free-end vertically swingable blades pivoted to said blocks to cooperate therewith in shearing the wires, and operating means for said blades.

5. In a wire bound box blank machine, 20 binding wire cutters comprising swinging free end blades adapted to swing down into the spaces between blanks and to project under the binding wires bridging said spaces and to swing up to shear said wires, means 25 above said wires for cooperating with said blades in shearing the wires, and operating means.

6. In a wire bound box blank machine, a slide arranged above and transversely of the 30 path along which the wire bound blanks advance, a stationary bar adjacent to said slide, means for reciprocating said slide, pairs of blocks, one block of each pair forming a shear block and having a free end 35 swinging cutter blade pivoted thereto, and blade swinging and controlling links pivoted to the blades and to the other blocks of said pairs, corresponding blocks of said pairs being secured to and adjustable longitudinally 40 of said slide and the other blocks of said pairs being secured to and adjustable longitudinally of said bar.

7. A wire bound box blank machine comprising several cutters for severing the binding wires, a rocking member operatively 45 connected with the several cutters for driving the same, stapler operating means provided with a periodically reciprocating part to drive said rocking member, a slide yieldingly maintained in normal position and 50 normally holding said rocking member from operative position with respect to said part whereby said cutters are normally inactive, a step by step feeder for advancing the box 55 blanks and provided with a device moving therewith and locating the rear end of a stapled box blank with respect to said cutters, said device arranged to move said slide to a position with the rocking member in 60 operative relation to said part, and a trip for releasing said slide from said device for automatic return to normal position.

8. A wire bound box blank machine comprising binding wire cutting mechanism, a 65 movable member connected with said mecha-

nism for operating the same, a stapler having means for periodically operating the same provided with a periodically reciprocating part for driving said movable member to actuate said mechanism on a wire cutting operation, a carrier for said movable member having a limited range of movement, said carrier normally maintaining said movable member in inoperative position with respect to said reciprocating part whereby 75 said cutter mechanism is normally inactive, means for returning said carrier to said normal position when moved therefrom and released, and a step by step feeder for the box blanks provided with a projection for 80 moving said carrier to and temporarily holding the same at a position wherein said member is operatively located with respect to said part, said carrier being provided with a trip for automatically releasing the carrier 85 from said projection to permit return of the carrier to normal position, substantially as described.

9. A wire bound box blank machine, comprising binding wire cutting mechanism, a 90 movable member connected to actuate said mechanism, a device for operatively engaging said member to drive said mechanism on a wire cutting and return operation, said device reciprocating periodically in a fixed 95 path, a carrier for said movable member and normally maintaining the same out of said fixed path whereby said mechanism and said movable member are normally inactive, and a feeder for the box blanks provided with 100 a part carried forward thereby to force said carrier to abnormal position with said member located in the path of said device, said carrier having a limited range of movement along the path of said feeder and being provided with a trip for automatically releasing the carrier from said part for return to its 105 normal position, means being provided for returning the carrier to normal position when released.

10. A wire bound box blank machine, comprising a step by step feeder for the box blanks provided with a part moving forward therewith, a slide block having a limited range of movement along the path of said 115 feeder, binding wire cutting mechanism, a cutting mechanism operating member carried by said block, a stapler and its actuating means having a driver for said operating member periodically moving in a fixed path, 120 and means for yieldingly holding said block in and returning the same to normal position, said member being normally held from said fixed path by said block, said part being arranged to force said block from normal position and to hold the same with said member in the path of said driver when the rear end of the stapled blank is in certain 125 relation to the cutting mechanism, a tripping device being provided between the block and 130

part for automatically releasing the block from the part.

11. A wire bound box blank machine having a periodically movable box blank feeder 5 and a periodically movable stapler; said machine comprising a rack moving in unison with the stapler and reciprocating in a fixed path, normally-inactive binding wire cutting mechanism having driving means including a toothed sector to mesh with and be rocked by said rack to drive the cutting mechanism, said sector being normally held from the path of said rack, and means for moving said sector into the path of said rack 10 and maintaining the rack and sector in temporary operative relation.

12. A wire bound box blank machine having a periodically movable box blank feeder and a periodically movable stapler; said machine comprising a rack moving in unison with the stapler and reciprocating in a fixed path, normally-inactive binding wire cutting mechanism having driving means including a toothed sector to mesh with and be rocked 20 by said rack to drive the cutting mechanism and having an elongated front end tooth to be engaged by the rack end to initiate the sector swing, said sector being normally held from the path of said rack, and means for moving said sector into the path of said rack 25 and maintaining the rack and sector in temporary operative relation.

13. A wire bound box blank machine having a step by step box blank feeder and a periodically movable stapler; said machine comprising a spring-held slide block having a limited movement along the path of the feeder, said feeder having a projection to move said block and temporarily hold the 35 same from its normal position, a trip and cam mechanism whereby the block is automatically released from said projection for return to normal position, normally-inactive binding wire cutting mechanism, and driving means for said cutting mechanism controlled by said block, said block normally maintaining said means from operative relation with said cutting mechanism, said block arranged to throw said means temporarily 40 into operative relation with said cutting mechanism when said block is held from its normal position by said projection.

14. A wire bound box blank machine, comprising a step by step blank feed having a projection bearing a certain relation to the end of a stapled blank, a stapler, binding wire cutting mechanism, a toothed driver for said cutting mechanism periodically movable in unison with the stapler, 55 cutting mechanism operating connections embodying a toothed member adapted to mesh with and be actuated by said driver to drive the cutting mechanism but normally out of mesh and operative relation therewith 60 whereby the cutting mechanism is normally 65 inactive, and means positively controlled and moved by said projection to temporarily shift to and hold said toothed member in operative relation to said driver to mesh therewith and cause a wire cutting operation 70 of said mechanism.

15. A wire bound box blank machine, comprising several cutters, one for each binding wire, a slide connected with said several cutters for simultaneously moving 75 the same on their cutting and on their return strokes, a movable member connected with said slide for reciprocating the same, a periodically movable driver for said member for moving the same to operate said cutters, said movable member and driver being normally out of operative relation whereby the cutters are normally inactive, a step by step feed for the blanks provided with a part positively moved forward by the feed, 80 and means arranged to be moved from normal position by said part to bring said member and driver temporarily into operative relation for driving the cutters when a stapled box blank has assumed a certain position with respect to said cutters.

16. A wire bound box blank machine, comprising binding wire cutting mechanism, a rock shaft having a link connection with said mechanism for actuating the same, said 95 shaft provided with a toothed sector for actuating the same, a stapler, a rack moving with said stapler for meshing with said sector to drive said shaft, a movable carrier for said shaft and whereby the same is normally held with said sector out of the path of said rack, and a blank feed having a part to move said carrier to position with the sector in the path of the rack.

17. A wire bound box blank machine, comprising a box blank feed, a carrier having a limited range of movement along said feed, means yieldingly holding the carrier in normal position and for returning the same thereto, said feed having a part to move the carrier from normal position and to hold the same temporarily in abnormal position, means whereby the carrier is automatically released from said part for return to normal position, binding wire cutting 110 mechanism, driving means for actuating said mechanism, and operating connections between said driving means and said cutting mechanism, said operating connections thrown into and from operative relation 115 with said driving means by said carrier, substantially as described.

18. A wire bound box blank machine, comprising binding wire cutting mechanism embodying an operating and controlling bar, 125 a rock shaft having operating connection with said bar for reciprocating the same, said shaft provided with a lateral arm for rocking the same, a stapler, a reciprocatory cutting-mechanism driver moving with the 130

- stapler to engage said lateral arm and rock said shaft to drive the cutting mechanism, a carrier for said rock shaft, said carrier being normally held in position with said 5 arm out of the path of said driver, and a box blank feed having a part to move said carrier and hold the same temporarily in position with said arm in the path of said driver.
- 10 19. A wire bound box blank machine, comprising a box blank feed, a slideway arranged adjacent thereto and longitudinally thereof, a slide block confined to and movable in said slideway and yieldingly held at 15 its limit of movement in one direction, said feed provided with a part to slide said block from normal position and hold the same temporarily in abnormal position, trip means whereby said block is automatically 20 released from said part for return to normal position, normally-inactive binding wire cutting mechanism and its operating connections, and driving means for said 25 connections, the operative relation between said connections and said driving means being controlled by the position of said slide block, substantially as described.
20. A wire bound box blank machine, comprising a box blank feed, binding wire 30 cutting mechanism embodying several cutter blocks held against movement toward the blank feed and each having a cutting edge transversely disposed with respect to the feed and all arranged in approximate 35 alignment at the same side of the said feed, free-end cutter blades, one for each block and fulcrumed thereto and normally arranged transversely of said feed and at the same side thereof as said blocks, mechanism 40 for simultaneously moving said blocks in tandem transversely of the feed, and controlling means for said blades for causing the same to open and close with respect to the blocks to receive the binding wires between the blades and blocks and to sever the 45 wires, by the said movement of the blocks.
21. A wire bound box blank machine, comprising a horizontal box blank feed, and binding wire cutting mechanism embodying 50 a cutter block above said feed and movable horizontally and transversely thereof, means for reciprocating said block, said block having a horizontally disposed cutting edge above said feed, a free-end cutter blade ful- 55 crumed to said block and normally arranged horizontally above said feed, and controlling means for said blade for swinging the same vertically as the block is reciprocated horizontally, substantially as described.
22. A wire bound box blank machine, 60 comprising a horizontal box blank feed, and binding wire cutting mechanism embodying a cutter block above said feed and moving horizontally and transversely thereof, means for reciprocating said block, said block having a horizontally disposed cutting edge above said feed, a free-end cutter blade fulcrumed to said block and normally arranged horizontally above said feed, said 65 blade having a cutting edge notched near the free end of the blade, and controlling means for said blade for swinging the same vertically as the block is reciprocated horizontally, substantially as described.
23. A wire bound box blank machine, 70 comprising a box blank feed, a stapler, a support transversely arranged across and provided with cutter blocks having cutting edges permanently located outside of the path of the feed and transversely arranged 75 with respect thereto, transversely-arranged free-end cutter blades fulcrumed to said blocks respectively, to cooperate with said edges thereof in severing binding wires, means to longitudinally move said support 80 to carry the blocks and blades transversely of the binding wires to positions with the wires between the blocks and respective blades, and controlling means for said 85 blades for swinging the same into the path 90 of the feed between the binding wires and for opening and closing the blades to and from the feed path and with respect to the blocks for the purposes substantially as described, as said support is moved longitudinally.
24. A wire bound box blank machine, comprising a box blank feed, a stapler, a bar arranged transversely of the feed, several cutter blocks carried by said bar, means 100 for rigidly clamping the blocks to and whereby said blocks are rendered independently adjustable toward and from each other and longitudinally of said bar, each block providing a cutting edge transversely arranged with respect to said feed and to one side of the path thereof, cutter blades fulcrumed to said blocks, respectively, and normally arranged transversely of said feed 105 and at the same side thereof as said edges, said blades arranged to move into the path of said feed and between the binding wires and then laterally to receive the wires between the blades and edges and then upwardly to sever the wires against the edges, 110 operating means, and blade controlling means.
